(57) **CLAIM**

The ornamental design for a storage bin for recyclables, as shown and described.

DESCRIPTION

FIG. 1 is a front elevational view of the storage bin for recyclables of the present invention;

FIG. 2 is a rear elevational view of the storage bin for recyclables of FIG. 1;

FIG. 3 is a right side elevational view of the storage bin for recyclables of FIG. 1, the left view being a mirror image thereof;

FIG. 4 is a top plan view of the storage bin for recyclables of FIG. 1;

FIG. 5 is a bottom plan view of the storage bin for recyclables of FIG. 1; and,

FIG. 6 is a top, front, right side perspective view with one of the bins partially removed.

1 Claim, 4 Drawing Sheets

FIG. 2
